(57) **CLAIM**

The ornamental design for a personal computer, as shown and described.

DESCRIPTION

FIG. 1 is a perspective view of front, bottom and right side of a personal computer showing our new design;

FIG. 2 is a perspective view of rear, bottom and left side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of rear, bottom and left side thereof, with lid open;

FIG. 10 is a front view thereof, with lid open;

FIG. 11 is a top view thereof, with lid open;

FIG. 12 is a right side view thereof, with lid open;

FIG. 13 is a perspective view thereof, with lid being rotated after it is open;

FIG. 14 is a bottom view thereof, with lid closed after it is open and rotated;

FIG. 15 is a left side view thereof, with lid closed after it is open and rotated; and,

FIG. 16 is a right side view thereof, with lid closed after it is open and rotated.

The broken lines shown are included for the purpose of illustrating the unclaimed portions of a personal computer and form no part of the claimed design.
